BANK PROTECTING DEVICE

Christian J. Meunier and Harold Bomboy,
New Orleans, La.

Application September 4, 1934, Serial No. 742,700

20 Claims. (Cl. 20—1.01)

Our invention has for an object to protect from robbery banks and other places where money is kept and handled, as for example, the cashiers' departments of counting houses, stores, factories, mills, etc.

Further, it is an object of our invention to provide a cashier's counter with means to guard the money and valuables thereon against theft by enclosing the money and/or valuables so that access thereto may not again be had save at the will of someone who is outside the influence of the bandits.

Further, it is an object to provide means to stop the bandits from getting the money even if the cashier, for one reason or another, wishes to give it to them and to put it entirely beyond the cashier's control.

Further, our invention has for an object to provide a money counter with a closure or cover and means operable at a number of different places in and about the building, or even at places remote from the building in which the protected counter is located for actuating the closure or cover in a manner to enclose and protect the funds.

Again, it is an object to provide a counter in the general form of a roll-top desk, the top of which is automatically closed and locked upon closing an electric circuit that is arranged to be closed from a number of places, and in which provision is made to eject from the counter anything which would be in the way of and likely to prevent the top from closing down and becoming locked; a further object is to accomplish this result without injuring the cashier.

Further, it is an object to provide an auxiliary door for the bank safes, which door may be automatically closed and locked upon the approach of a bandit without necessitating the closure of the outer doors of the safes, which outer doors bear the time locks.

Further, it is an object to provide an auxiliary door for the vault or safe which is composed of armor plates held rigidly as a unit but spaced apart, the plates being perforated at intervals, the perforations of one plate being located out of register with those of the opposite plate in order to prevent passage of bullets through the perforations and yet permit air to pass through, so if someone becomes imprisoned in the vault when the door is automatically closed he will not become suffocated.

A further object is to provide an alarm bell in each cashier's counter and in the safe or vault,

with means to set the bells into operation immediately the operating circuit is closed to begin the closing of the counters and door in order that those in the vicinity may be warned and a cashier may remove his hands before the cover closes completely down on the counter.

Further, it is an object to provide means to permit the covers to close down and lock even though the cashier does not get his hands out of the way in time, and to do this without injuring the cashier's hands.

A further object is to provide a bank protecting system in which, after the operating circuit has once been closed and the counters and doors locked, they may not be restored to their normal positions save by the use of a key or keys in the hands of someone located at a place sufficiently remote as not to be under the control or influence of the bandits. Such a person, for instance, may be the Chief of Police who retains the keys at some secret location, for example.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawings, in which:

Figure 1 is a plan view, largely in diagram, illustrating bank tellers' or cashiers' cages set up.

Figure 2 is an enlarged front elevation of a single counter unit with the cover open.

Figure 3 is a cross section of the same on line 3—3 of Figure 2.

Figure 4 is a view similar to Figure 3 with the top or cover closed.

Figure 5 is a section on the line 5—5 of Figure 3.

Figure 6 is a vertical section on the line 6—6 of Figure 3.

Figure 7 is a detail perspective view of a portion of the invention.

Figure 8 is a detail section on the line 8—8 of Figure 4.

Figure 9 is a detail section through one of the back check latches.

Figure 10 is a detail view illustrating how the switch 53 is operated on to open the circuit.

Figure 11 is a detail view showing the spring means for holding the flap 50 down.

Figure 12 is a front elevation of a vault or safe equipped with our safety door.

Figure 13 is a section on the line 13—13 of Figure 12.

5 Figure 14 is a detail horizontal section on the line 14—14 of Figure 12.

Figure 15 is an enlarged detail of the catch releasing mechanism for the safe door.

Figure 16 is a detail sectional view of a roll-top or curtain construction which may be used.

10 Figure 17 is a diagrammatic view of the electric circuits employed.

In the drawings in which like numerals of reference designate like parts in all the figures, 15 represents the usual cashier's cages and 2 indicates the counters of which there may be any number desired and which may be constructed and operated as separate units or as one. In Figure 17 I have diagrammatically illustrated the 20 operating shafts for the covers of the several counters in the several cashier's cages arranged for operation as one by a single motor, but as the construction of each counter is substantially the same we shall in the further description of our 25 invention describe in detail only a unit counter which is best illustrated in Figures 2—5 inclusive, by reference to which it will be observed that the counters are securely mounted on supports 3 which are preferably firmly embedded in a suitable 30 foundation or base 4 of concrete or other suitable material.

The counter in its entirety is preferably constructed of metal adapted to resist explosives, such as armor plate or the like, and it may be of any desired form and contain any of the usual details such as partitions, money recesses, etc., as are found in cashiers' furniture. As these details, per se, form no part of our invention, we have not disclosed them specifically nor shall 40 we refer to them in detail herein.

In its general aspect a counter comprises a chambered bed 5, a chambered back wall 6, a chambered top wall 7 and chambered sides 8. The spaces within the chamber portions are utilized 45 to contain the operating machinery and the roll-top or curtain which constitute portions of our invention.

As will be seen particularly by reference to Figure 3, the numeral 9 indicates the roll-top 50 or curtain which is preferably formed of interlocking steel bars constituting a flexible structure, the forward end of which is connected to a front cross bar 10 that carries a rubber strip 11, the purpose of which will later appear.

55 Suitable roller guides 12 are provided over which the roll-top or curtain 9 passes. The inner end of the curtain carries a cross bar 31 which cooperates with a stop 32 to limit the outward movement of the inner end of the curtain and prevent the same from being pulled out from beneath the top 7 when in the closed position. The inner end of the roll-top or apron 9 beyond the bar 31 carries a section 9x which is adapted to be rolled up on a drum 38 that is 60 carried by a shaft 28, the purpose of which will soon appear.

The sides 8 are provided with grooves 13 in which the ends of the cross bar 10 slide. Other grooves 13x are provided in which the side edges 70 of the roll-top or flexible curtain 9 ride.

Arranged at suitable intervals within the grooves 13 are spring latches 14 (constituting reverse movement checking means) shown in detail in Figure 9, these latches having beveled 75 ends so that the cross bar 10 can slide by in pass-

ing downwardly but cannot pass upwardly. The spring latches 14 are designed to be withdrawn to permit the upward movement of the cross bar 10 as the roll-top or curtain 9 is "wound up" and to this end a bell crank lever 15 is provided 5 for each latch. The bell cranks 15 of all latches are connected by flexible cables 16 to an arm 18 on the shaft 17 of the lock 20. The lock 20 is of such construction that when the key 21 is inserted and turned the lock shaft turning wheel 19 will be connected with the shaft 17, but when the key is out the wheel 19 cannot function to turn the shaft 17. The lock may be of the general type of those employed on automobile door handles or of the so-called coincidental types 15 used in locking the gears and ignition circuits of automobiles. Since the general construction of the lock is of a well known type, a detailed illustration of the same is thought to be unnecessary in this case. 20

Referring again to Figures 3 and 7, it will be observed that 22 represents the counter closing shaft which is provided with a back check device comprising a ratchet 23 engaged by a pawl 24 for the purpose of preventing the shaft 22 from 25 turning backward while permitting it to turn forward when drawing down or closing the roll-top or curtain 9. The pawl 24, however, is arranged to be released when the key 21 is placed in the lock 20 and turned, by means of a flexible 30 cable 25 which is attached to a second arm 26 on the shaft 17.

The shaft 22 carries a gear 27, while the shaft 28 carries a similar gear 29. Between these gears, but arranged to engage only one of them 35 at a time, is the pinion 38 on the shaft of the motor 37 that effects the closing action of the roll-top or curtain 9. This closing action is transmitted to the roll-top or curtain 9 by means of one or more arms 33 secured to the shaft 22 40 and the cross bar 10 and located preferably adjacent the side wall or walls 8.

The motor 37, as best indicated in Figure 5 and Figure 6, is pivotally mounted on a vertical axis as at 35 to a support 34, and the motor has 45 an arm 36 by means of which it may be turned on its pivot to bring the pinion 38 into mesh with either the gear 27 or 29. Normally the pinion 38 is in mesh with the gear 27 but when the key 21 is inserted in the lock 20 and the wheel 19 50 is turned, the motor is rocked to put the pinion out of mesh with the gear 27 and into mesh with the gear 29. This movement may be accomplished by means of connecting rods 39 and 41, and a suitable bell crank 40 as best indicated in 55 Figure 7. The connecting rod 41 from the bell crank 40 is attached to the arm 26 on the lock shaft 17 so that when the lock shaft is turned for the purpose of withdrawing the latches 14 and releasing the pawl 24 it will at the same time 60 effect the shifting of the motor from the operative connection with the shaft 22 to the operative connection with shaft 28.

In order to throw off any obstructions on the edge of the counter which might prevent the bar 65 10 reaching its lowermost locked position we provide a hinged flap 50 that is hinged on a shaft 51 and fits within an opening in the bed 5 so that it will normally lie with its upper face flush with the upper face of the bed. When, however, 70 the electric circuit is closed (as will hereinafter more clearly appear) to energize the motor 37 which operates the shaft 22, the hinged flap 50 will be raised before the bar 10 comes into its proximity. The flap 50 which is normally held 75

down by suitable means, as for instance a volute spring 52, is raised by cams 48 on a shaft 47 which is operated by a mutilated worm gear 46 that meshes with another worm gear 45 on an intermediate shaft 43 that is driven through the medium of worm gears 42 and 44 from the shaft 22. In order to insure that the worm gear 45 shall take hold of the mutilated worm gear 46 when it is desired to begin the rising movement 10 of the cams 48 a suitable light spring, such as a volute spring 49, may be provided.

53 designates a circuit opening switch. This switch is of a well known type, such as is frequently used in closets for automatically turning on the light when a closet door is opened and which, when the closet door is closed, will automatically open the circuit. The switch 53 is arranged, however, to operate in a reverse manner to that of the closet door switch referred to. 20 That is to say, the spring action tends to keep the circuit closed instead of opening it. The switch 53 is so positioned that a finger 54 on one of the arms 33 will move the switch to open the circuit just as the bar 10 reaches its lowermost 25 position.

Referring now especially to Figure 17, it will be seen that we provide a main relay 55 having a magnet 56 connected in the circuit 63 which contains the source of electrical energy (preferably a storage battery) 62 and which contains the circuit closers 64. The circuit closers 64 are distributed at different points in and about the bank or other building which is to be protected in order that they may be operated by any of a 30 number of persons at different places. The circuit closers 64 may be of any type, some push buttons, some switches and others may be actuated by sound waves.

Thus it will be seen that when a circuit closer 40 64 is operated the magnet 56 of relay 54 will be energized to draw its armature 57 down into engagement with a fixed contact 61. This permits the latch 59 to be drawn over by the spring 60 to hold the armature 57 down mechanically. 45 A stop 59 limits the upward movement of the armature 57.

65 is the operating circuit. This circuit includes the battery 62, magnet 56, armature 57, fixed contact 61 and the magnet 67 of a second relay 66. The circuit 65 is provided with master fuses 77 in box 74 for opening the circuit in event of a dangerous overload on the wires.

The relay 66 is provided for the purpose of closing a power circuit 70-71 which contains 55 one or more sirens 72 and gongs 73 which may be located on the outside of the building being protected and/or at the office of the Chief of Police of the city or the office of the captain of the precinct in which the protected building is located. The signals 72 and 73 are preferably operated from the outside power lines 70 which supply the electricity for lighting and other purposes. So far as described, it will be seen that when a circuit closer 64 is operated relay 55 closes 60 and locks, and at the same time relay 66 becomes energized to close the circuit 70-71 and operate the distant signals.

In Figure 17 we have illustrated diagrammatically the invention as applied to three counter units and one bank vault auxiliary door unit. It is obvious, however, that if all of the counters of the bank are operated from a single motor, only one motor need be provided, such as 37. Each counter unit's circuit opening switch 53 is connected in series in the sub-circuit 76 of the motor 75

37, the sub-circuit 76 including the fuses 78 in the sub-circuit fuse box 75.

By referring now more particularly to Figures 12 and 13, the construction of the auxiliary door for the vault or safe will be clearly understood. The wall of the safe is built to enclose an operating motor 79 which is geared down through a reducing gear train 105-106-107-108 to engage the teeth 128 of the rack bar 109, the rack bar being secured to the sliding door 110.

10 In Figures 12 and 13 the number 109 designates the vault (which may be of the ordinary construction and, per se, constitutes no part of our invention) and 103 indicates the vault door frame to which the usual doors 101 (which carry the 15 time locks, etc.) are hinged. The frame 103 is recessed at 102-102 for the reception of the sub-frame or casing 113 in which the door 110 operates. The casing 113 includes grooved trackways 104 in which the door slides. The sliding door 20 110 is preferably formed with a chamber or space 111. The side plates of the door are provided with air holes 112, those of one side plate being out of register with those of the other so that the bandit may not by firing through the holes in 25 the outer face of the door cause the bullets to pass through holes in the inner face of the door.

The sub-frame 113 is provided with fixed rods 114. These rods 114 serve as a holding means for cooperating with the pivot catches 115. These 30 catches are pivoted on fixed pivots 116, and normally rest against stops 117, they being held against the stops by suitable means, as for example volute springs 118 (see Figure 15). The pivoted catches 115 have beveled ends 120 and 35 catch rod receiving recesses 119, the latter lying over the catch rods 114 when the door is closed.

Suitable means are provided for unlatching the door when desired. We prefer to arrange the latches 115 in two groups, an upper and a lower 40 group. When this is the case the means for releasing the latches may consist of connecting rods 121 and 122 for the respective groups, the connecting rods at their adjacent ends being provided with wedges 123 operating in guides 124. 45 The wedges 123 cooperate with an operating wedge 125 on a bar 126 mounted to slide within the chamber of the door in suitable guides 127. The door is recessed at 129 and in this recess is mounted the latch releasing or disengaging wheel 50 130 and the lock 132 which cooperates therewith. The lock is of a construction whereby when the key 133 is inserted and turned the wheel 130 will be connected with the shaft of a pinion 131 55 so that by turning the wheel 130 the pinion 131 is turned to move the wedge operating bar 126 in a direction to force the wedges 123 apart and thereby rock the catches 115 so as to disengage the rods 114, it being understood that the bar 126 has rack teeth 137 for meshing with the 60 pinion 131.

Returning now to a further examination of the diagram, Figure 17, it will be noted that the safe door operating motor 79 is preferably actuated by an auxiliary battery 80 through the medium of 65 relay 81 one winding of the magnet 82 of which is connected in the circuit 65. The relay 81 has its armature 83 connected through a second winding of the magnet 82 to battery 80.

70 84 designates the fixed contact of the relay 81 which is connected by one of the wires 92 of the sub-circuit to a pole changing switch controlled by a suitable lock 88.

75 85 and 86 designate circuit opening switches 75

- which normally hold the circuit closed, but which are actuated by the door for opening the circuit. For instance, when the sliding door is in the closed or locked position it will have engaged 5 the button of the switch 85, pushed it in and opened the circuit at that place, whereas as the sliding door reaches the fully opened position the rack bar 109 will push the button of switch 86 in and open the circuit at that point.
- 10 87 designates generally the lock controlled reversing or pole changing switch, which includes a shaft 89 that carries the pole changers 90, the latter cooperating with the contact groups 93-96 and 94-95. The wire 92 from the contact 84 runs to the left hand contact 95 and the right hand contact 96 of the switch 87, while the other wire 92 from battery 80 runs to the right hand contact 95 and the left hand contact 96 of the switch 87. One of the wires 91 from the motor 79 is connected directly to the right hand contact 93 and indirectly through switch 85 to the left hand contact 93 of the reversing switch 87; the other wire 91 from motor 79 connects directly to the left hand contact 94 of the switch 25 87 and indirectly through switch 86 to the right hand contact 94, see Figure 17. When the key 97 is inserted in the lock 88 the shaft 89 may be turned to reverse the connections of switch 87 and thereby effect a reversal of the motor 30 79. Normally when the key 97 is out of the lock 88, the parts are positioned as shown in diagram in Figure 17 so that the motor 79 is ready at all times to move the open door 110 to the closed position.
- 35 88 Each counter unit is provided with a signal bell 136 connected to ring whenever the motor 37 of that unit is energized. Each counter unit is also provided with a circuit closer consisting of a fixed contact 98 and a movable contact 99. 40 These contacts 98 and 99 are associated with the lock 26 so that when the key 21 is inserted to enable the shaft 17 to be turned, as soon as the shaft has been turned to its maximum degree, the circuit between contact 98 and 99 will be 45 closed temporarily to short-circuit the switches 53 and enable the current to flow to the motor 37 for resetting purposes.
- Another pair of contacts 134 and 135 are provided in the circuit 65 in parallel with contacts 50 57-61 and these contacts 134-135 are associated with the lock 26 similarly to the contacts 98 and 99 and are adapted to be closed at the same time.
- Operation
- 55 55 Assume the parts to be positioned as diagrammatically illustrated in Figure 17, and that a bandit or bandits have entered the bank for the purpose of robbing it. Anyone seeing or knowing 60 of the presence of the bandits, and being adjacent a circuit closer 64, will close the circuit 63. Circuit 63 being closed by the circuit closer, current will then flow from battery 62 through circuit 63 to energize magnet 56 of relay 55. This 65 causes armature 57 of that relay to be pulled down into engagement with contact 61 and at the same time permits latch 58 to latch the armature down so that any opening of the circuit closer 64 will not affect the following action that 70 takes place. Circuit 65 being now closed between 57 and 61, current flows from the battery 62 through the wires 65, thereby energizing magnet 67 of relay 66 and closing the outside signal circuit 70-71 to sound the siren 72 and ring the 75 gong 73. Current also flows to each of the mo-

tors 37 of the respective counter units. As the motors 37 are in driving engagement with the shafts 22 of the respective units they will thus begin to draw down the roll-tops or curtains 9 to close the counters as hereinbefore described. 5 As soon as the curtain of a counter has been closed down, switch 53 is opened and held open by the finger 54, thus breaking the motor circuit. As soon as circuit 65 has been energized current will also flow through the alarm bell 136 of the 10 unit and warn the cashier to get his hands out of the way. When the circuit 65 is closed by relay 55 the current also flows through one of the windings of magnet 82 of the relay 81, thereby closing the circuit between contacts 83 and 84 of 15 relay 81. Current then flows from battery 80 through the sub-circuit 92, further energizing magnet 82 to hold the armature 83 down. (A latch 138 similar to latch 58 of Figure 17 may be used if desired.)

20 Current now flows from battery 80 through motor 79 via the pole changing switch. This starts motor 79 to turn for the purpose of closing the door 110. As soon as the door 110 shall have reached its closed position the circuit 25 of the motor 79 will be opened by switch 85 as before described. All of the counters and the safe or vault have now been protected against the bandits. Alarms 72 and 73 are still ringing, but current has been shut off from motors 37 30 and 79.

In order to restore the parts to their normal positions after the trouble is over, someone releases the armature 57 of relay 55 by moving latch 58 manually out of engagement with armature 57, thereby opening circuit 65 and consequently relay 66 opens the sub-circuit 71, stopping the signals 72 and 73. He next inserts the key 21 into the lock 26 and turns wheel 19 to release latches 14, pawl 24 and shift motor 37 to a 40 position to drive shaft 28 of the respective counter unit. As soon as these parts shall have been shifted contacts 134 and 135 will be closed and contacts 98 and 99 closed, thereby re-energizing circuit 65 to permit current to flow around the 45 switches 53 to the motors 37, thereby raising or winding up the roll-tops or curtains 9 of the respective units. As soon as these curtains shall have been raised the wheel 19 is turned back and contacts 134-135 and 98-99, respectively, open 50 up to de-energize the circuit 65.

During this time the circuit of motor 79 remains closed at relay 81. The key 133 is inserted into the lock 130 and the catches 115 released. The key 97 is now inserted into the lock 55 88 and shaft 89 is rocked to change the polarity of the current to the motor 79, thereby reversing it and moving the door back to the open position under the power of the motor. The door 110 may be mounted on roller bearings 139 so that 60 if desired it may be moved to the open position manually. After the door starts to open key 133 is withdrawn so as to free the catches 115 and allow them to assume their normal positions.

Having opened the door, the shaft 89 is turned 65 back to restore the switch 87 to the position shown in Figure 17, after which the key 97 is removed as is also key 21. Latch 138 in relay 81 is now moved to release armature 83, whereupon the parts will be restored to the normal position, 70 as shown in Figure 17, and the cycle of operation will have been completed.

The fuse boxes 74 and 75 are provided for the usual safety purposes, it being understood that under normal operating conditions these fuses do 75

not blow, but if for any reason an overload on the lines should occur, one or more of the fuses will blow to protect the circuits. It should also be understood that the circuit closers 64 are normally open and when not engaged remain open.

5 A suitable signal 140 (see Figure 17) may be located in the vault at any convenient place to be set into operation when motor 19 is energized, thereby warning persons within the vault that the door is being closed.

10 By including the magnet 56 of the relay 55 in the local motor operating circuit 65, as well as in the circuit 63 (the magnet being double wound if desired), the latch 58 may be dispensed with 15 and the relay 55 become self-operating when circuit 65 is opened, the magnet 56 when energized by closed circuit 65 serving to keep that circuit closed between armature 57 and contact 61.

15 The latches 58 and 138 are in the nature of 20 safety devices to obtain a positive closing of the circuits even though the operating magnets should, accidentally or otherwise, become de-energized before the cycles of operations of the remaining mechanisms are completed; or if the 25 magnets 56 and 82 should be single-wound magnets, then the latches would be necessary, particularly if the circuit closures 64 are of the self-opening type.

20 In the practical use of our invention it is the 30 intention that the master key or keys be kept outside of the bank at some source where they will not be under the control or influence of the bandits, as hereinbefore mentioned, and furthermore in order to prevent the bandits from interfering with the operations of the safety devices, 35 all wiring, the fuse boxes and switches contained in the system will be well protected by embedding the same in suitable armor or concrete and locating the fuse boxes and relays in concealed 40 places. Since the only wires which enter or leave the building are the power wires 70 and signaling sub-circuit wires 71, it matters little if these wires are cut, since that would not interfere with the proper functioning of the counter and vault protecting instrumentalities.

45 By locating the control switches at various 50 places about the bank at convenient locations to the employees and officers of the bank, anyone knowing of the presence of robbers can throw the switch to set the system into operation, thereby shutting off access to the money in the tellers' cages and in the vault so that no matter what else the bandits may do they will not be able to get any money. As the obtaining of 55 money is the thing that bandits hold up a bank for, the fact that they are thus prevented from getting the funds will stop them and other bandits knowing thereof from holding up banks so protected. As the cashier is the one who is usually molested and whose life is usually in danger, the fact that he cannot open the counters or vaults even under duress will cause all bandits, when they come to know this, to leave all places protected by our invention entirely alone.

60 65 Not only may the circuit closing switches be located within the bank proper, but they may be located in public places where anyone seeing a bank held up may operate the switch to set the safety system into operation. Therefore if a bank is held up by a number of bandits and all 70 of the bank clerks and executives are under duress so that none of them can operate the secret switches, nevertheless an outsider seeing the hold-up can close one of the public switches and effect 75 the operation of the safety system.

While we prefer to use a roll-top closure in our invention, the design or form of the counter may be such that a cylindrical segment or rigid closure may be used. Other modifications of the structure will readily occur to those skilled in the art 5 without departing from the spirit of the invention as set forth in the appended claims. While we have disclosed the roll-top operated by two arms, one at each side, it is obvious that we do not wish to be limited to any particular number 10 of arms employed for this purpose. In disclosing our invention in this application we have endeavored to disclose a preferred workable embodiment, as illustration thereof, and it is not our intention to be understood as limiting the 15 invention to the specific details of construction and arrangement of parts shown, save in so far as those limitations may be included in the appended claims.

20 While we have described our invention as 25 adapted for use in banks, counting houses and other fixed places where money is handled over the counter, we do not desire to be limited to these particular uses as the invention may be used wherever it may be found to be adaptable. 25 For instance, the auxiliary safe door may be employed as an auxiliary door for armored cars which carry money and valuables.

30 While in this application we have disclosed our invention as including a protecting mechanism 30 for a vault (see Figures 12, 13, 14, and 15) we do not in this application make claim to the vault feature specifically, as that constitutes the subject-matter of our divisional application filed January 31, 1935, Serial No. 4396. 35

From the foregoing description, taken in connection with the accompanying drawings, it is thought that the complete construction, operation and advantages of our invention will be clear to those skilled in the art to which it appertains. 40

What we claim is:

1. Mechanism for operating and controlling the movement of a movable closure of a money counter, said mechanism comprising means including an electric motor for closing and opening the 45 same, means to hold the closure against opening movement after it has started on its closing movement, a master lock mechanism, an electric circuit for actuating said motor, at least one circuit closer for effecting a closing of said circuit 50 to operate the motor to move the movable closure to close the counter, and means cooperative with said master lock mechanism for releasing said closure holding means and effecting the action of said motor to reopen the counter. 55

2. Mechanism for operating and controlling the movement of a movable closure of a money counter, said mechanism comprising means including an electric motor for closing and opening the counter, means to hold the closure against opening movement after it has started on its closing movement, a master lock mechanism, an electric circuit for actuating said motor, at least one circuit closer for effecting a closing of said circuit to operate the motor to move said movable closure to close the counter, and means cooperative with said master lock mechanism for releasing said closure holding means and effecting the action of said motor to reopen the counter, 60 and means for throwing off from the counter 70 obstructions to the complete closing of said movable closure.

3. Mechanism for operating and controlling the movement of a movable closure of a money counter, said mechanism comprising means in- 75

cluding a closure closing shaft, a closure opening shaft and an electric motor to operate said shafts, gear connections between said motor and said shafts, said motor being shiftably mounted for connection with one shaft at a time, means normally maintaining said motor connected to said closure closing shaft, a back check device cooperative with closure closing shaft, an electric circuit for said motor, a lock cooperating with said means for the purposes described, at least one circuit closer for closing said electric circuit to actuate the motor and close said closure, and means cooperative with said lock for shifting said motor from said closing shaft to said opening shaft to effect the reopening of the counter.

4. Mechanism for operating and controlling the movement of a movable closure of a money counter, said mechanism comprising means including a closure closing shaft, a closure opening shaft and an electric motor to operate said shafts, gear connections between said motor and said shafts, said motor being shiftably mounted for connection with one shaft at a time, means normally maintaining said motor connected to said closure closing shaft, a back check device cooperative with closure closing shaft, an electric circuit for said motor, a lock cooperating with said means for the purposes described, at least one circuit closer for closing said electric circuit to actuate the motor and close said closure, and means cooperative with said lock for shifting said motor from said closing shaft to said opening shaft and for again closing the circuit to energize said motor.

5. Mechanism for operating and controlling the movement of a movable closure of a money counter, said mechanism comprising means including a closure closing shaft, a closure opening shaft and an electric motor to operate said shafts, gear connections between said motor and said shafts, said motor being shiftably mounted for connection with one shaft at a time, means normally maintaining said motor connected to said closure closing shaft, a back check device cooperative with closure closing shaft, an electric circuit for said motor, a lock cooperating with said means for the purposes described, at least one circuit closer for closing said electric circuit to actuate the motor and close said closure, means cooperative with said lock for shifting said motor from said closing shaft to said opening shaft to effect the reopening of the counter, reverse movement checking means cooperating directly with said closure, and means also cooperative with said lock for releasing said back check device and said reverse movement checking means to permit the motor to reopen the counter.

6. Mechanism for operating and controlling the movement of a movable closure of a money counter, said mechanism comprising means including a closure closing shaft, a closure opening shaft and an electric motor to operate said shafts, gear connections between said motor and said shafts, said motor being shiftably mounted for connection with one shaft at a time, means normally maintaining said motor connected to said closure closing shaft, a back check device cooperative with closure closing shaft, an electric circuit for said motor, a lock cooperating with said means for the purposes described, at least one circuit closer for closing said electric circuit to actuate the motor and close said closure, means for opening the motor circuit when the counter is closed, means cooperative with said lock for

shifting said motor from said closing shaft to said opening shaft and for again closing the circuit to energize said motor, reverse movement checking means cooperating directly with said closure, means also cooperative with said lock for releasing said back check device and said reverse movement checking means to permit the motor to reopen the counter. 5

7. Mechanism for operating and controlling the movement of a movable closure of a money counter, said mechanism comprising electrically operated means to close and open the counter, said means including an electric motor, a closure moving mechanism including a pair of operating shafts, one for closing the counter and the other for opening it, an electric motor normally operatively connected to said counter closing shaft, means including a lock device for effecting the operative relations between said motor and said shafts and having means in virtue of which when said lock device is unlocked said motor may be shifted into operative connection with either shaft, and an electric circuit for said motor which includes circuit closers.

8. Mechanism for operating and controlling the movement of a movable closure of a money counter, said mechanism comprising electrically operated means to close and open the counter, said means including an electric motor, a closure moving mechanism including a pair of operating shafts, one for closing the counter and the other for opening it, an electric motor normally operatively connected to said counter closing shaft, means including a lock device for effecting the operative relations between said motor and said shafts and having means in virtue of which when said lock device is unlocked said motor may be shifted into operative connection with either shaft, an electric circuit for said motor which includes circuit closers for closing the motor circuit, and means including said lock device for controlling the opening action of said motor.

9. Mechanism for operating and controlling the movement of a movable closure of a money counter, said mechanism comprising means for actuating the closure and including a motor and operative connections between said motor and the closure, means including a lock device for normally maintaining said motor connected for moving the closure to close the counter, closure latches, an electric circuit including said motor and at least one circuit closer for effecting operation of said motor, means to open the circuit to cut out said motor when the counter has become closed, and means cooperative with said lock device when unlocked for shifting the motor connections and reclosing the circuit to move the closure to reopen the counter. 45

10. In apparatus of the character described, a cashier's counter having a movable closure, means for actuating said closure and including a motor and operative connections between said motor and said closure, means including a lock device for normally maintaining said motor connected for closing the counter, closure back check latches, an electric circuit including said motor and at least one circuit closer for effecting operation of said motor, means to open the circuit to cut out said motor when the counter has become closed, and means cooperative with said lock device when unlocked for shifting the motor connections and reclosing the circuit to reopen the counter, said movable closure having a yieldable edge-strip for purposes described. 60 65 70

11. In apparatus of the character described, 75

- a cashier's counter having a downwardly closing movable closure, means for actuating said closure and including a motor and operative connections between said motor and said closure, means including a lock device for normally maintaining said motor connected for closing the counter, closure back check latches, an electric circuit including said motor and at least one circuit closer for effecting operation of said motor, means to open the circuit to cut out said motor when the counter has become closed, means cooperative with said lock device when unlocked for shifting the motor connections and reclosing the circuit to reopen the counter, and means to throw off any obstructing articles from the counter which might be in the way of said closure as it is being closed.
12. In apparatus of the character described, a stationary counter having a downwardly closing closure, means to move said closure to its closed and open positions, and means to throw off from the counter any articles which may obstruct the full closing of the closure.
13. In apparatus of the character described, a stationary counter having a downwardly closing closure, means to move said closure to its closed and open positions, and means to throw off from the counter any articles which may obstruct the full closing of the closure, said throwing off means comprising a hinged flap and means to operate it in time before the closure reaches its closed position and to restore it after the closure has started to move to its open position.
14. In apparatus of the character described, a stationary counter having a downwardly closing closure, means to move said closure to its closed and open positions, means to throw off from the counter any articles which may obstruct the full closing of the closure, and locked means for holding the closure against reverse movement after it has started to close.
15. In apparatus of the character described, a counter having a downwardly closing closure, means to move said closure to its closed and open positions, means to throw off from the counter any articles which may obstruct the full closing of the closure, said throwing off means comprising a hinged flap and means to operate it in time before the closure reaches its closed position and to restore it after the closure has started to move to its open position, and locked means for holding the closure against reverse movement after it has started to close.
16. Mechanism for operating and controlling the movement of a movable closure of a money counter, said mechanism comprising a motor for closing and opening the counter, an electric circuit for said motor, means to lock said closure in the closed position, means controlled by said closure for opening the motor circuit when the closure has become locked, and means cooperative with said circuit and including a key-controlled lock device for effecting a reverse action by the motor and for releasing said closure lock.
17. Mechanism for operating and controlling the movement of a movable closure of a money counter, said mechanism comprising means including an electric motor for moving the closure, a primary electric circuit including at least one circuit closer and a source of energy and a magnet of a first relay, a motor circuit including an armature and a fixed contact of said relay and including a source of energy, whereby when a circuit closer is closed said relay will close the motor circuit, said relay including means to hold the motor circuit closed even after the primary circuit is again opened, a switch in the motor circuit and controlled by the movable closure to open the motor circuit when the counter is closed, and a key releasable lock mechanism having means to reclose the motor circuit around said switch and having means to reverse the action of the motor to open the counter when the lock mechanism is unlocked by its key.
18. Mechanism for operating and controlling the movement of a movable closure of a money counter, said mechanism comprising a power line circuit, a motor for operating the closure, a local circuit for said motor and including a source of energy, an actuating circuit including circuit closers at different locations and including a source of energy, a relay whose magnet is connected in said actuating circuit and whose armature and fixed contact are connected in said local circuit, means cooperative with the closure for opening the motor circuit thereof when the closure is fully closed, a key-controlled lock device for the motor and its circuit which device when unlocked will cause the motor to move the closure to open the counter.
19. Mechanism for operating and controlling the movements of a movable closure of a money counter and giving an alarm in cooperation with the closing movement thereof, comprising a power line circuit; alarm signals; an alarm signal circuit in which said signals are contained; a motor for operating the closure; a local circuit for said motor and including a source of energy; an actuating circuit including circuit closures at different locations and including a source of energy, a first relay whose magnet is connected in said actuating circuit and whose armature and fixed contact are connected in said local circuit; a second relay whose magnet is connected to said local circuit to be energized when said local circuit is closed by said first relay and whose armature and fixed contact are connected in said alarm signal circuit; means cooperative with the closure for opening said local circuit when the closure is fully closed; a key controlled lock device for the motor, which device when unlocked will effect the motor to set it to a position for moving the counter to its open position; said second relay being adapted to open the alarm circuit when the local circuit is open and said first relay being adapted to open the circuit through the magnet of said second relay when the magnet of said first relay is de-energized; and means for again closing said local circuit to actuate said motor to open the counter without again closing said alarm circuit.
20. Mechanism for operating and controlling the movements of a movable closure of a money counter and giving an alarm in cooperation with the closing movement thereof, comprising a power line circuit; alarm signals; an alarm signal circuit in which said signals are contained; a motor for operating the closure; a local circuit for said motor and including a source of energy; an actuating circuit including circuit closures at different locations and including a source of energy, a first relay whose magnet is connected in said actuating circuit and whose armature and fixed contact are connected in said local circuit; a second relay whose magnet is connected to said local circuit to be energized when said local circuit is closed by said first relay and whose armature and fixed contact are connected in said alarm signal circuit; means cooperative with the closure for opening said local circuit when the closure is fully closed; a key controlled lock device for the motor,

which device when unlocked will effect the motor to set it to a position for moving the counter to its open position; said second relay being adapted to open the alarm circuit when the local circuit is open and said first relay being adapted to open the circuit through the magnet of said second relay when the magnet of said first relay is

de-energized; and means cooperative with said lock device for again closing said local circuit to actuate said motor to open the counter without again closing said alarm circuit.

CHRISTIAN J. MEUNIER.
HAROLD BOMBOY.
